UNITED STATES PATENT OFFICE

2,003,748

TOY

William Ellsworth Hopkins, Pittsburgh, Pa.

Application October 13, 1934, Serial No. 748,255

1 Claim. (Cl. 46—37)

This invention relates to a toy and consists in the provision of a toy including a dart, a sling for throwing or shooting the dart, and an improved head construction for the dart for the explosion of percussion wafers or caps.

The invention, together with its objects and advantages, will be best understood from a study of the following description taken in connection with the accompanying drawings wherein:

10 Figure 1 is a side elevational view of the dart.
Figure 2 is a top plan view thereof.

Figure 3 is a plan view of the blank from which the head of the dart is formed.

Figure 4 is a detail view taken substantially on 15 the line 4—4 of Figure 5.

Figure 5 is a side elevational view of the sling and a part of the dart showing the manner and means of projecting the dart.

Figure 6 is an enlarged detailed sectional view 20 of an end of the dart.

Referring to the drawings by reference numerals, it will be seen that the dart comprises a stem 10 provided at one end with a vane or feather 11. At the other or opposite end thereof the stem 10 of the dart is provided with a head 12. The head 12 is formed from a blank of metal or other suitable material cut, shaped, and dimensioned to provide a substantially rectangular casing having top, side and end walls and adapted to fit onto a reduced end portion of the dart stem 10 as shown in Figures 1, 2 and 6, one of the side walls 12a and the bottom wall 12b and top wall 12c are provided with extensions 13 that are folded in overlapping relation as suggested in Figure 6 to 30 provide an end wall for the head. Side walls 12a of the head are provided with extensions 14 that fold inwardly and in overlapping relation to the folded extensions 13 serving to retain said extensions 13 in proper folded relation.

40 The top wall 12c of the head is provided with an entrance slot 15 provided for the chamber 16 formed by the head 12, and the side walls of the head are provided with ribs 17 to act as a guide and retaining means for the percussion wafer or cap introduced into the chamber 16 through the opening 15.

45 Suitably secured to the end of the stem 10 within the chamber 16 is an anvil 18 which is in the form of a disk having an integral pin driven into the stem 10 as shown in Figure 6.

The extensions 13 of walls 12b and 12c are apertured to slidably accommodate the rod 19 of a hammer 20 operating within the chamber 16. The hammer 20 cooperates with the anvil 18 in a manner thought apparent for exploding the percussion wafer or cap upon forcible contact of the hammer stem 19 with a target or the like.

5 For projecting or shooting the dart, there is provided a sling consisting of a suitable handle member 21 formed of wood or other suitable material and about one end is disposed an elastic band 22 suitably retained in engagement with the handle 21 through the medium of a suitable strap or loop 23. On its underside the stem 10 of the dart is provided with a suitably located nail, pin, or shank 24 with which the band 22 is adapted to be engaged as clearly shown in Figure 5 for the purpose of projecting or shooting the dart 10.

10 As is thought to be apparent, to shoot the dart, 20 the tail or vane equipped end of the stem 10 is grasped between the thumb and finger of one hand, the handle 21 of the sling being held in the other hand, and the hook or projection 24 being engaged in the free end of the band 22. Thus, 25 with the parts so held and as suggested in Figure 5, it will be apparent that a pull on the stem 10 to the right in Figure 5 will expand the band 22 until sufficient tension has been placed thereon. By releasing the tail or vane-equipped end of the 30 dart, the contraction of the band 22 will project or throw the dart with great force.

Further, with a percussion cap arranged with-in the chamber 16 of head 12 and held against 35 the anvil 18 by the ribs 17, the forceful engage-ment of the stem 19 of the hammer with a target or the like arresting the flight of the dart, a force is applied sufficient to produce an explosion.

40 What is claimed is:

A dart including a stem provided at its tail end with a vane and at its head end with an apertured hollow head forming a chamber, an anvil secured directly to said head end and extending into the chamber, a gravitating hammer operating with-in the chamber and having a stem operating through an opening in an end wall of the cham-ber to provide a striking point, said head being provided in one side thereof with a slot for the introduction of a percussion cap into the cham-50 ber between the anvil and the hammer head, and means on opposed walls laterally of the chamber for retaining a percussion cap in flat contact with the anvil.

WILLIAM ELLSWORTH HOPKINS. 55
